ELECTRIC DISCHARGE TUBE

Gustav Zecher and Johannes Bruijnes, Eindhoven, Netherlands, assignors, by mesne assignments, to General Electric Company, a corporation of New York

Original application April 15, 1929, Serial No. 355,334. Divided and this application August 25, 1934, Serial No. 741,398. In the Netherlands June 14, 1928

1 Claim. (Cl. 176—122)

This invention has reference to electric discharge tubes and more particularly to electric glow discharge tubes containing metal vapour, preferably mercury vapour.

5 The invention has for its object to cause the metal vapour enclosed within the discharge tube to take part intensively in the discharge. For this purpose, according to the invention, a heating element is arranged adjacent to the path of 10 discharge between the electrodes. The discharge tube may contain, in addition to a metal vapour, a gas, preferably a rare gas. Another object of the invention is to lessen the chances of condensed metal vapour forming on the walls of the 15 tube, which is accomplished by reason of the higher and more uniform temperature of operation maintained by the heating element referred to above.

The heating element is arranged outside the 20 discharge tube within a re-entrant part of the latter.

The wall of the discharge tube may be at least partly of material that is transparent to ultraviolet rays.

25 Preferably the heating element acts as a current limiting resistance. In some instances it may be used to entirely replace such a resistance, thus saving energy.

The arrangement of a heating element adjacent the path of discharge is of great advantage 30 in connection with glow discharge tubes, as a higher metal vapour pressure can thus be attained. In discharge tubes having a discharge of a kind other than a glow discharge, for example 35 a positive column discharge, a sufficient vapour pressure can always be ensured by a sufficiently intense current which cannot be resorted to in the case of glow discharge tubes.

The invention will be readily understood by 40 reference to the accompanying drawing in which

an embodiment of the invention is diagrammatically illustrated in elevation.

The glow discharge lamp 1 has two electrodes 7 and 8 helically wound together which are fixed to and taken out of the lamp by two small tubes 13 and 14 at the reentrant part 15 of the discharge tube. The gaseous filling of this lamp contains mercury vapour which is heated by a heating element 16 that is arranged outside the discharge tube within the re-entrant part 15 10 and which is connected to the leading-in wires 17 and 18 by which a separate heating current can be supplied.

Three important results follow the use of the 15 heating element described as part of this invention—the electrodes discharge more readily and at a lower impressed voltage; the operation of the tube as a light source is steadied; and finally the carrier vapor for the discharge itself enters more freely and efficiently in the reaction to emit 20 radiation.

This application is a division of co-pending application, Serial Number 355,334, filed April 15, 1929 and granted August 28, 1934; Patent Number 1,971,890.

25 What we claim as new and desire to secure by Letters Patent of the United States is:—

A glow discharge lamp comprising a transparent envelope containing helically wound electrodes each concentric to the axis of the envelope, and supporting means for said electrodes provided with a single heater coil carried adjacent the windings of the electrodes and exterior to the envelope for increasing the temperature of the discharge normal to said electrodes, said 30 heater coil being coextensive with said electrodes and the discharge path between said electrodes.

GUSTAV ZECHER.
